The ornamental design for a desk lamp with race car motif, as shown and described.

DESCRIPTION

FIG. 1 is a perspective view of a desk lamp with race car motif according to the invention in which the lamp shade has the form of a wing used on a racing car;

FIG. 2 is a front elevational view of the lamp of FIG. 1; FIG. 3 is a rear elevational view of the lamp of FIGS. 1 and 2;

FIG. 4 is a top plan view of the lamp of FIGS. 1-3; FIG. 5 is a right side view of the lamp of FIGS. 1-4, the left side view being a mirror image thereof;

FIG. 6 is a cross sectional view taken along line 6—6 of FIG. 2 showing the exact contours or configurations of the lamp shade members not visible in FIGS. 1-5;

FIG. 7 is a front elevational view of an alternative embodiment of the new desk lamp with race car motif design;

FIG. 8 is a rear elevational view of the lamp of FIG. 7;

FIG. 9 is a top plan view of the lamp of FIGS. 7 and 8;

FIG. 10 is a right side view of the lamp of FIGS. 7-9, the left side view being a mirror image thereof;

FIG. 11 is a cross sectional view taken along line 11—11 of FIG. 7 showing the exact contours and configurations of lamp shade members not visible in FIGS. 7-10;

FIG. 12 is a front elevational view of a further alternative embodiment of the new lamp design;

FIG. 13 is a rear elevational view of the lamp of FIG. 12;

FIG. 14 is a top plan view of the lamp of FIGS. 12 and 13;

FIG. 15 is a right side elevational view of the lamp of FIGS. 12-14, the left side elevational view being a mirror image thereof;

FIG. 16 is a left side elevational view of the lamp of FIGS. 12-15;

FIG. 17 is a cross sectional view taken along line 17—17 of FIG. 12 showing the exact contours or configurations of lamp shade members not visible in FIGS. 12-16; and,

FIG. 18 is a cross sectional view taken along line 18—18 of FIG. 12 showing exact contours or configurations of lamp shade members not visible in FIGS. 12-16.

Details shown in dashed dotted lines are for illustrative purposes only and form no part of the claimed design.
